(57) **CLAIM**

(51) **LOC (10) Cl.** **10-04**

I claim the ornamental design for a quality sensor for vehicles,
as shown and described.

(52) **U.S. Cl.**

DESCRIPTION

USPC **D10/53**

FIG. 1 is a perspective view of a quality sensor for vehicles
showing my new design;

(58) **Field of Classification Search**

FIG. 2 is a front view thereof;

CPC F02D 19/0628; F02D 19/0684; F02D
19/0634; F02D 19/084; F02D 41/0025;

FIG. 3 is a back view thereof;

F02M 65/00; F02M 69/465; F02M 55/025;

FIG. 4 is a left side view thereof;

F02M 2200/14; F02M 2200/0611

FIG. 5 is a right side view thereof;

USPC D10/96, 97, 101, 102; 73/61.43,

FIG. 6 is top view thereof; and,

73/114.38, 114.52–114.54, 114.68,

FIG. 7 is a bottom view thereof.

73/114.71–114.73, 114.43, 149;

123/406.3, 1 A, 685, 406.47,

123/406.37–406.39, 406.45; 141/94, 95,
